ALBERT SLATEN, OF MINNEAPOLIS, MINNESOTA

BUTTER CUTTER

Application filed April 19, 1930. Serial No. 445,605.

This invention relates to butter cutting machines, and the primary object is to provide an efficient, practical, and comparatively simple and economically constructed machine, for use in restaurants, hotels, and cafes, for dividing a large block of butter, such as a conventional pound unit, into small pieces or "pats" to be served the individual guests. Further and more specific objects will be disclosed in the course of the following specification, reference being had to the accompanying drawings, in which:

Fig. 1 is a top or plan view of the machine.

Fig. 2 is a front elevation of the machine, the major portion of the base section being broken away.

Fig. 3 is a sectional elevation as seen substantially on the irregular line 3—3 in Fig. 2.

Fig. 4 is a cross section on the line 4—4 in Fig. 3.

Fig. 5 is an enlarged detail section on the line 5—5 in Fig. 2.

Referring to the drawings more particularly and by reference characters, A designates a main frame, which is suitably secured to and supported on a base or standard B. The main frame is made up of a horizontally disposed section 6, that is mounted on the standard B, and a vertical end section 7, that is fastened to the section 6, as by screws 8. The frame section 6 carries a tray 9 to slidably support the butter block, and this tray is readily removable for cleaning purposes.

The frame section 6 is provided at its rear end with a laterally extending arm 10 that forms a bearing support for the rear end of a shaft 11. The forward end of the shaft is journaled in a bearing portion 12 formed at an intermediate point in an arm 13 that extends laterally from and is integral with the frame section 7. The forward end of the shaft 11 carries a wheel or disk 14 having an eccentric pin 15 which operates in a slot 16 of a cutter frame 17 which is trunnioned upon a short shaft 18 mounted in the outer end of the arm 13. The pin 15 is preferably provided with an enlarged head 19, which engages against the front face of the cutter frame. The rear end of the shaft 11 is pro-

vided with a cam 20, which is rotated by a crank arm 21 having a handle 22.

Slidably mounted in the arms 10 and 13 and under the shaft 11 is a toothed rack bar 23, the rear end of which has a roller 24 for engagement against the irregular face of the cam 20. The rack bar 23 is yieldingly held rearwardly with the roller 24 in engagement with the cam by a spring 25 (see Fig. 3). The upper edge of the rack bar 23 is provided with teeth 26 which intermittently move the pusher head forwardly in a manner presently to be described.

Slidably and rotatably mounted upon the shaft 11 is a carrier 27 from which extends an integral arm 28 supporting the pusher head 29. An adjustable set screw 30 is secured in the under side of the arm 28, and slidably engages the adjacent flange of the tray 9, so as to hold the pusher head slightly spaced above the bottom of the pin, to provide clearance between the members 9 and 29. When the set screw 30 is in contact with the tray 9 the head 29 should be in alignment with the rectangular opening of the frame 7, as shown in Fig. 2. The forward face of the pusher head 29 is provided with right angularly disposed grooves 31, which divide it into four substantially equal sections. The purpose of these grooves is to permit the head 29 to advance to an extreme forward position with respect to a pair of crossed cutting wires 32—33 which are mounted in the frame 7, and divide the opening therein equally into four parts. The wires 32—33

may be secured in any suitable manner, but I have shown a novel method for doing so, as illustrated particularly in Fig. 5, in which figure it will be seen that one end of the divider wire rests in a small groove 34 in the front face of the frame 7, and extends through a perforation in the front end of a short screw 40 which is slidable in the frame 7, and screws into a nut 42 which operates against the rear face of the frame 7. Thus, by turning the nut 42 the screw 40 is pulled forward, thus exerting a clamping action upon the wire 32. As shown in Fig. 5, it is also desirable to bend the extreme end of the wire over, as indicated at 41, which bend

ing will also tend to prevent the wire from being pulled out of place.

Adjustably secured to the carrier 27 is a small plate 43 having slots 44 engaged by set screws 45 which screw into the carrier 27. When these screws are loosened the plate 43 may be longitudinally adjusted with respect to the carrier, and such adjustment is preferably done by means of an adjuster screw 35 which extends through a flange 36 of the carrier, and has threaded engagement with a flange 37 at one end of the plate 43. After the desired adjustment has been made by turning of the screw 35, the set screws 45 are again tightened up to render the plate 43 rigid with respect to the carrier. Secured in the plate 43 is a screw 38 which serves as a pivot for a pawl 39, which engages the teeth 26 of the rack bar 23. This pawl 39 has a lug 46 at its forward end which is so disposed that it will engage the carrier casting 27 to prevent the pawl from dropping below its lowermost operative position with respect to the rack bar. The pawl 39 is also provided with a finger piece 47 which extends upwardly about the carrier, as shown in Figs. 1, 3, and 4, and has for its purpose to disengage the pawl 39 from the rack bar when it is desired to move the carrier 27 rearwardly. When the member 47 is released the pawl 39 will, of course, drop back into operative position with respect to the rack bar teeth 26.

Before the tray 9 can be removed for cleaning purposes it is of course necessary to first remove the pusher head 29, and this is done by lifting the same upwardly and swinging it over to the other side of the shaft 11. When the tray has been re-inserted in the machine the pusher head is returned to its operative position by swinging it back into place. When this is done, however, provision must be made to prevent the breakage of any part by reason of the pawl 39 striking one of the teeth 26 from the side, and this I have done by grinding or cutting off one corner of the pawl, as shown at 48 in Fig. 4. Thus, when the carrier is swung into operative position the pawl 39 is held up to some extent by the lug 46, but if it should swing against one of the teeth 26 instead of into one of the notches between the teeth, the cut away portion 48 will cause it to ride over the tooth so that it will not meet with any positive resistance.

The cutter head or frame 17, as previously mentioned, pivots upon the stub shaft 18, and when the crank 21-22 is rotated the eccentric pin 15 operates in the slot 16 to impart a vertical oscillating movement to the cutter frame. The frame 17, as shown particularly in Fig. 1, operates in close proximity to the frame 7, and has a cutting wire 49 which preferably operates in a plane immediately adjacent to the plane of the cut-

ting wires 32-33. One end of the wire 49 is anchored, as at 50, to a lug 51 on the cutter frame, and from thence extends downwardly to and rearwardly through a perforation 52, as shown in Figs. 2 and 3. The wire 49 then extends across the opening of the cutter frame to a perforation 53, through which it extends, and terminates at a hook 54 which operates through a second lug 55 at the other end of the cutter frame, and is there engaged by a thumb screw 56 which bears against the lug 55 and may be used to tighten or release the wire 49, as occasion may require.

It may here also be noted that the frame 17 is provided with a pair of inclined supporting fingers 57-58 which engage the small pieces of butter after they have been cut from the large block by the wires 32-33, and 49, to separate them from each other and from the block so that they will drop down in individual pieces into the ice bowl or other receptacle in which they are to be kept until served.

The operation of the device may be described as follows: When a block of butter, such as a pound unit, is to be cut up into small pieces, usually known as "pats", the pusher head 29 is first moved back into its rearmost position. The block of butter is then placed in the tray 9, and the carrier 27 is moved forwardly until the pusher head 29 engages the rear end of the block of butter. By turning the crank 21 the operator now not only reciprocates the cutter head 17, but also imparts an intermittently reciprocating action to the rack bar 23. This movement successively advances the carrier 27 step by step until the pusher head 29 is in its foremost position against the cutting wires 32-33, at which time the entire block of butter has been cut up into small pieces. It will be understood, however, that the parts are so arranged, and the cam 20 is so synchronized with respect to the cutter frame 17 that the carrier 27 will not be advanced during the cutting movement of the frame 17. In other words, the cam action upon the rack bar 23 is such that the butter block will be advanced through the frame 7 only when the cutting wire 49 is in an idle position above the butter, and that there will be no forward movement or action imparted to the butter block while the forward end thereof is being severed by the cutting wire 49. The thickness of the butter pats being cut will of course be the same as the length of the teeth 26, and if it is desired to change the thickness of the butter pieces so that more or less pats may be cut from each pound of butter the rack bar 23 can readily be substituted by one having shorter or longer teeth, as the case may be. It is always desirable, however, regardless of the size of the pieces being cut, to divide the butter block in such a way that the pats cut from both ends thereof will be as uniform

in size as possible, and to this end I have provided the adjusting plate 37 previously described, so that the position of the pawl 39 with respect to the pusher head 29 may be 5 slightly adjusted. Thus, for instance, should the block of butter to be cut not be in a proper position with respect to the cutting frame 7, so that the first cut by the wire 49 will result in a cut which is too thin or too thick, the set 10 screws 45 are first loosened and the screw 35 is then adjusted so that the head 29 will be in a proper operating position when the first vertical cut is made into the butter.

It is understood that suitable modifications 15 may be made in the structure as disclosed, provided such modifications come within the spirit and scope of the appended claims. Having now therefore fully illustrated and described my invention what I claim to be 20 new and desire to protect by Letters Patent is:

1. A butter cutting machine comprising a 25 butter support, a stationary cutter frame at one end of the support, a movable cutter frame adjacent to the stationary frame, a shaft journaled longitudinally of the machine, means operative upon rotating the shaft to actuate the movable cutter frame, a toothed rack bar disposed parallel with said 30 shaft, a carrier tilttable and slidable upon the shaft with a pusher head operative over the butter support, a pawl on the carrier for engagement with the rack bar, a screw disposed parallel with respect to the rack bar for adjusting the pawl with respect to the carrier, screw means for securing the pawl in variously adjusted positions on the carrier, and means for actuating the rack bar.

2. A butter cutting machine comprising a 40 butter support, a stationary cutter frame at one end of the support, a movable cutter frame adjacent to the stationary frame, a shaft journaled longitudinally of the machine, means operative upon rotating the shaft 45 to actuate the movable cutter frame, a toothed rack bar disposed parallel with said shaft, a carrier tilttable and slidable upon the shaft with a pusher head operative over the butter support, a pawl on the carrier for engagement with the rack bar, means for reciprocating the rack bar and a stop member limiting the downward movement of the rack bar engaging end of the pawl, said pawl having 50 a beveled corner for sliding contact with an edge of a rack tooth whereby it may slip into operative position on the rack when the carrier is tilted into operative position.

3. A butter cutting machine comprising a 55 butter support, a stationary cutter frame at one end of the support, a movable cutter frame adjacent to the stationary frame, a shaft journaled longitudinally of the machine, means operative upon rotating the shaft to actuate the movable cutter frame, a toothed rack bar disposed parallel with said

shaft, a carrier tilttable and slidable upon the shaft with a pusher head operative over the butter support, a slotted adjusted plate having a screw in the slot releasably and adjustably securing the plate upon the carrier, an 60 adjusted screw for adjusting the position of the plate on the carrier when said first mentioned screw is released, a pawl carried by said adjuster plate for engagement with the rack bar, and means for actuating the rack 65 bar.

Signed at Minneapolis, Minnesota, this 17th day of April, 1930.
